(57) **CLAIM**

The ornamental design for a tablet case, as shown and described.

DESCRIPTION

FIG. 1 is a front and top perspective view of a tablet case, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 2;

FIG. 10 is another perspective view of the tablet case in an alternative position around a tablet environment; and,

FIG. 11 is an exploded view of the tablet case from FIG. 1. The broken lines in the figures illustrate portions of the tablet case that form no part of the claimed design. In FIG. 10, the broken lines also depict a tablet environment that form no part of the claimed design. The dash-dot-dash lines in FIGS. 2 and 9 are for the purpose of depicting boundary lines of the enlarged view and form no part of the claimed design.
